UNITED STATES PATENT OFFICE.

ROBERT D. PIKE, OF SAN FRANCISCO, CALIFORNIA.

GRINDING-MACHINE.

1,212,552.

Specification of Letters Patent. Patented Jan. 16, 1917.

Application filed March 20, 1916. Serial No. 85,375.

To all whom it may concern:

Be it known that I, ROBERT D. PIKE, a citizen of the United States, residing in the city and county of San Francisco and State 5 of California, have invented certain new and useful Improvements in Grinding-Machines, of which the following is a specification.

The present invention relates to a grinding machine, and more particularly to an 10 apparatus for pointing or otherwise grinding the ends of rods, as, for example, electric arc carbons and the like. The pointing of such carbons, and particularly those used in projection apparatus, requires extreme 15 care, in order to insure absolute equality in the finished product, since a point incorrectly centered, or of abnormal size, causes trouble and waste in the use of the carbon. Moreover, on account of the brittleness of 20 the carbons, great care must be exercised to support them properly at all times, and to relieve them from all shocks and jars which would cause breakage.

The object of the invention, therefore, is 25 to provide a machine which automatically grinds the ends of carbons to correctly formed points, and which, by its continuous action, performs the desired work with the greatest possible efficiency.

30 Although the machine is designed primarily for the pointing of carbons, and is so illustrated and described hereinafter, nevertheless it may also be employed for pointing or grinding other objects, and may 35 be readily adapted to a great variety of uses without necessitating any changes in the essential features of the invention.

In order to comprehend the invention, reference should be had to the accompanying 40 sheets of drawings, wherein—

Figure 1 is an elevation of the machine. Fig. 2 is a plan view of the same. Fig. 3 is a vertical section, enlarged, taken on the line 3—3 of Fig. 2 and viewed in the direction of the arrows. Fig. 4 is a part sectional view, enlarged, of one of the chucks. Fig. 5 is an end elevation of the same. Fig. 6 is a detailed view of one of the chuck jaws and the operating sleeve therefor. Fig. 7 is an 50 enlarged detail of one of the supporting brackets for the chucks. Fig. 8 is a rear elevation of the same. Fig. 9 is a plan view of the same. Fig. 10 is an enlarged detail

of the final carbon guiding means. Fig. 11 is a part section enlarged of the initial carbon guiding means. Fig. 12 is a plan view of the same.

In the drawings the reference numeral 1 indicates a suitably constructed base, to which is attached a vertically disposed column 2 and a laterally projecting bracket 3—Figs. 1 and 3 of the drawings. The bracket 3 provides a bearing for concentric shafts 4 and 5 carrying respective driving means 6 and 7, shown in the drawings as 65 pulleys. Upon the inner ends of said shafts 4 and 5 are mounted respectively bevel gears 8 and 9, which mesh with coacting bevel gears 10 and 11 fixed respectively upon the lower ends of concentric vertical sleeves 12 70 and 13, surrounding the central supporting column 2. Suitable thrust bearings 14 are provided at the lower ends of said vertical sleeves to support the weight thereof, and suitable radial bearings 15 are provided at 75 the upper ends of said sleeves.

The outer sleeve 13 carries at its upper end a turret 16—Figs. 1, 2 and 3 of the drawings, to which the carbon holding chucks are attached in the following manner: Mounted 80 for sliding movement in a direction radial with respect to said turret 16, in suitably formed guides 17, (Figs. 3, 7, 8 and 9 of the drawings), is a bracket 18 carrying on its outer end a bearing 19, shown as comprising two diametrically divided parts held together by screws 20. Said bracket 18 has an upwardly projecting lug 21, bored and interiorly threaded to receive an adjusting screw 22, said screw passing through 90 and having a bearing in a cross piece 23 bridging the guides. Thrust collars 24 and a lock nut 24' are provided on said adjusting screw 22, on either side of the bridge 23, to retain said screw in its proper lineal position. The outer end of the adjusting screw 22 is preferably formed to receive a wrench as shown at 25. The guides 17 are preferably mounted upon the turret 16 with the interposition of resilient cushions 17' of 100 rubber or other similar material, to absorb the shocks due to the grinding action.

In the drawings, four carbon holding chucks are shown disposed about the periphery of the turret 16, although it is to be 105 understood that any number of said chucks

may be used within the limits of structural and operative practicability, each chuck being independently adjustable radially of the turret by the means described above. Each 5 carbon holding chuck is rotatably mounted in the bearing 19 of the sliding bracket 18, said chuck being provided for this purpose with a reduced exterior diameter 26 (Fig. 4 of the drawings) bounded at each end by 10 thrust flanges, or bearings 27. Said chuck is inclosed within a shell 28 upon the upper end of which is carried a bevel gear 29, said gear meshing with a large bevel gear 30, (Figs. 1 and 3 of the drawings), mounted 15 upon the upper end of the vertical sleeve 12. Thus it will be seen that by the slow rotation of the turret 16, driven by the pulley 7, the carbon holding chucks are carried around in a continuous circular path, and by the more 20 rapid rotation of the gear 30, driven by the pulley 6, the carbon holding chucks are individually rotated at a high rate of speed within their respective journals 19.

The mechanism of the carbon holding 25 chucks, all of which are identical, may be described as follows, with reference to Figs. 4 and 5 of the drawings. The shell 28 carries at its outer or lower end a ring 31 in which are formed substantially longitudinal 30 inclined guide-ways 32, each of said ways being adapted to receive and support a sliding jaw 33, the inner surface thereof being parallel with the axis of the chuck and formed with teeth 34 for gripping the carbon, or other stock to be operated on, as 35 shown in Fig. 5 of the drawings. Three of said jaws 33 are illustrated in the preferred form of the chuck, although more may be used, if desired. Within the shell 28 of the 40 chuck is a slidably mounted sleeve 35—Fig. 4 of the drawings, formed at its inner end with an outwardly projecting flange 36. An annular space 37 is left between the shell 28 and the body of the sleeve 35, within which 45 is a spring 38, preferably acting between spaced thrust collars 39 and 40 bearing respectively against the end flange 36 of said sleeve 35 and the end 28' of the shell 28. The sleeve 35 is connected with the jaws 33 50 by means of tongues 41, Fig. 6 of the drawings, projecting from the inner ends of said jaws and seating in suitably formed slots 42 in the flange 36 of said sleeve, and having sliding movement therein radially with respect to the chuck. Thus it will readily be 55 seen that an inward lineal movement of the sleeve 35, as caused by the spring 38, moves the jaws 33 within their inclined guides 32, which movement results in moving said jaws 60 inwardly toward the center of the chuck; and opposite movement of the sleeve 35 causes an outward movement or expanding of said jaws. By reversing the inclination 65 of the guides 32 and the action of the spring 38, the jaws may be made to close upon an

outward movement of the sleeve 35, if such movement be more desirable than that described above.

The outer ends of the sleeves 35 of the carbon holding chucks carry cam followers 43 rotatably mounted in suitable bearings 44 and adapted to follow a face cam 45 carried at the periphery of a fixed table 46 mounted upon the upper end of the vertical supporting column 2. Said cam 45 causes 70 the chucks to be opened and closed by raising and lowering the cam followers 43, as 75 said chucks are carried around by the rotation of the turret 16.

Projecting from the base 1 on one side 80 thereof is a bracket 47 (Figs. 1 and 2 of the drawings) which carries an arcuate guide plate 48. Said guide plate 48, as shown in 85 Figs. 11 and 12 of the drawings, is adjustably mounted upon the bracket 47, and secured thereto as by means of bolts 49, and is inclined, as shown, to a position perpendicular to the axis of the carbon 53 within the chuck, and its upper surface is serrated as 90 shown at 50, the teeth thereof being pointed in a direction opposite to that of the rotation of the turret 16. A slot 51 is provided in the upper face of said guide 48, and discharge apertures 52 extend from the bottom 95 of said slot through said guide for a purpose hereinafter set forth.

In the operation of the apparatus, when the cam follower 43 of a chuck rides upon the raised portion 45' of the cam 45 at the position A in Fig. 2 of the drawings, the 100 jaws of that chuck are then opened. When said chuck, by the rotation of the turret 16, is carried over the end of the guide 48, a carbon is dropped into the upper end of the chuck by the operator, or in any convenient 105 manner, not shown in the drawings. The carbon 53 falls through the chuck until its end rests upon the guide 48—as shown in Fig. 11 of the drawings, whereupon any soft 110 material adhering to the end of the carbon 53 is removed therefrom by the teeth 50 of said guide, and falls through the apertures 52. The cam follower 43 runs off the end 115 of the raised portion 45' of the cam before the carbon 53 reaches the end of the guide 48, and said carbon is thereby firmly clamped in the chuck in the desired lineal position for 120 grinding. At the position B—Figs. 2 and 3 of the drawings, the lower protruding end of the carbon 53 is carried across the face of 125 a preferably dished grinding wheel 54, said wheel being set obliquely with respect to said carbon, so that as said carbon is carried across the face of said wheel, and rotated upon its axis as described above, a point of 130 the proper form is formed upon said carbon. The grinding wheel 54 is preferably driven from a motor 55 in any convenient manner, as, for example, by a belt 56, and is mounted in such a manner as to provide for universal 135

adjustment thereof relative to the carbon 53 at said position B. For purposes of illustration I have shown this mounting of the grinding mechanism as comprising a fixed stand 57—Figs. 1 and 2 of the drawings, upon which is carried for vertical and horizontal adjustment a bracket 58 and upon this bracket in turn are mounted the grinding wheel 54 and the driving motor 55. 5 Suitable means are provided, as indicated at 59, for adjusting said bracket in a vertical arcuate path to move the grinding wheel toward or away from the carbon 53. A 10 similar grinding mechanism is preferably provided at the position C—Fig. 2 of the drawings, having a grinding wheel 54' and a driving motor 55', mounted upon a stand 57'. The positions of the grinding wheels 54 and 54' relative to the carbon 53 are 15 such that the point is roughly formed by the wheel 54 at the position B and finished by the wheel 54' at the position C. Immediately 20 after the carbon 53 is carried free of the grinding wheel 54', the cam follower 43 rides upon a short raised portion 45" of the cam 45, thereby momentarily opening the 25 chuck and allowing the carbon 53 to fall until its end rests upon a final guide plate 60, adjustably carried by a bracket 62, Fig. 30 2 of the drawings, extending laterally and upwardly from the base 1. This guide plate 60 is illustrated in Fig. 10 of the drawings as arcuate in form, disposed perpendicularly to the carbon 53 and provided with a tapered 35 arcuate slot 61 into which the point of the carbon 53 enters. The carbon is thus limited in its downward movement within the released chuck by the diameter of its point. The chuck is thereupon closed to again grip 40 the carbon, and the continued rotation of the turret 16 carries the pointed lower end of said carbon over the face of an end grinding wheel 63, said wheel being preferably driven by a motor 64—Fig. 1 of the drawings, 45 mounted on a suitably formed bracket 65 extending from and supported by the bracket 62. This grinding wheel 63 grinds off the end of the pointed carbon to the proper size, thereby insuring the proper 50 length of point. The chuck is thence carried to the position A—Fig. 2 of the drawings, where the carbon is released and allowed to drop into a discharge chute 66—Fig. 1 of the drawings, from whence it is 55 removed by any convenient means, and the chuck then assumes its original position, and is ready to be reloaded.

The operation of the machine is continuous at all times. The carbons are fed into 60 the chucks successively and are successively carried past the initial guiding plate 48, the two pointing wheels 54 and 54', the final guiding plate 60 and the end finishing wheel 63 by the rotation of the turret 16. Moreover, the individual chucks are continuously

rotated at relatively high speed by the gear 30. The machine therefore operates with the greatest possible efficiency.

I have hereinbefore described and illustrated my invention in its preferred form. 70 I do not wish, however, to be construed as limiting myself to said preferred form, for the reason that many changes may be made in the device without in any way affecting the principles of the invention, and I therefore 75 wish to be understood as claiming the invention as broadly as the state of the art will permit.

Having thus described my invention, what I claim as new and desire to protect by Letters Patent is:—

1. In an apparatus for the described purpose, the combination with a plurality of grinding means, of a device for holding the work to be ground, mechanism for moving 35 said holding device to carry the work successively into and out of the spheres of action of the grinding means, means for correctly positioning said work within said holding device prior to the first grinding 90 operation, and means for re-positioning said work within said holding device after said first grinding operation.

2. In an apparatus for the described purpose, the combination with a plurality of 95 grinding means, of a device for holding the work to be ground, mechanism for moving said holding device to carry the work successively into and out of the spheres of action of the grinding means, means for correctly positioning said work within said holding device prior to the first grinding 100 operation, and means for actuating said holding device to cause the same to release said work after said first grinding operation, 105 to enable said work to be re-positioned within said holding device.

3. In an apparatus for the described purpose, the combination with adjustable 110 grinding means, of a device for holding the work to be ground, means for rotating said holding device upon its axis, mechanism for moving said holding device to carry the work into and out of the sphere of action of the grinding means, and means for universally adjusting said grinding means relative 115 to said work.

4. In an apparatus for the described purpose, the combination with a plurality of 120 grinding means, of a device for holding the work to be ground, mechanism for carrying said holding device into and out of the sphere of action of the grinding means, means for adjusting said holding device on 125 said carrying mechanism, and adjustable devices for correctly positioning the work within said holding device.

5. In an apparatus for the described purpose, the combination with a plurality of 130 grinding means, of a device for holding the

- 4
- work to be ground, rotatable carrying mechanism for moving said holding device into and out of the sphere of action of the grinding means, and adjustable devices for 5 correctly positioning the work within said holding device before being carried into engagement with the grinding means.
6. In an apparatus for the described purpose, a rotatable turret, an adjustable bracket mounted in the peripheral region thereof, a chuck rotatably carried within said bracket, means for adjusting said bracket radially with respect to said turret, grinding means positioned in proximity to 10 said turret, and mechanism for rotating said turret to carry the work into operative relation with the grinding means.
7. In an apparatus for the described purpose, a rotatable turret, a bracket carried in 15 the peripheral region thereof, a resilient cushion interposed between said bracket and said turret, a device rotatably carried within said bracket for holding the work to be ground, means for rotating said holding device within said bracket, grinding means positioned in proximity to said turret, and mechanism for rotating said turret to carry the work into operative relation with the grinding means.
8. In an apparatus for the described purpose, a rotatable turret, a chuck rotatably mounted thereon for holding the work to be ground, grinding means positioned in proximity to said turret, a guide plate associated with said turret for positioning the work within said chuck, and mechanism for 25 rotating said turret to carry the work into operative relation with the grinding means.
9. In an apparatus for the described purpose, a rotatable turret, a rotatable chuck carried thereby for holding the work to be ground, grinding means positioned in proximity to said turret, an adjustable guide plate for positioning the work within said 30 chuck, and mechanism for rotating said turret to carry the work into operative relation with the grinding means.
10. In an apparatus for the described purpose, a rotatable turret, devices carried 35 thereby for holding the work to be ground, a grinding wheel positioned in proximity to said turret, said grinding wheel having a concave grinding face and being positioned with one edge of said face closer to said turret than the other, means for operating said grinding wheel, and mechanism for rotating said turret to carry the work across the operative face of said grinding wheel.
11. In an apparatus for the described purpose, a rotatable turret, devices carried 40 thereby for holding the work to be ground, a grinding wheel positioned in proximity to said turret, said grinding wheel having a concave grinding face and being adjustably mounted with respect to said turret, means 45 for operating said grinding wheel, means for universally adjusting said grinding wheel and mechanism for rotating said turret to carry the work into operative relation with the grinding wheel. 70
12. A pointing machine comprising a grinding wheel, a chuck for holding the work in inclined relation thereto, a guide for positioning said work within said chuck, and mechanism for moving said chuck to 75 carry the work from said guide to said grinding wheel. 75
13. A pointing machine comprising a plurality of grinding wheels, a chuck for holding the work in operative relation to said wheels, a guide for positioning said work within said chuck, and mechanism for moving said chuck to carry the work into operative relation successively with said grinding wheels. 80
14. A pointing machine comprising a grinding wheel, a chuck for holding the work in inclined relation thereto, a guide for positioning said work within said chuck, comprising an arcuate plate having a serrated upper surface, and mechanism for moving said chuck to carry the work across the surface of said guide plate and into operative relation with said grinding wheel. 85
15. A pointing machine comprising a chuck for holding the work to be pointed, grinding means for pointing said work, means for transversely grinding the end of the pointed work, and mechanism for moving said chuck to carry the work into operative relation successively with said point grinding means and said end grinding means. 90
16. A pointing machine comprising a chuck for holding the work to be pointed, a guide for positioning the work within said chuck, grinding means for pointing the work held by said chuck, a second guide for re-positioning the work within said chuck, means for transversely grinding the end of the pointed work, and mechanism for moving said chuck to carry said work successively from said first guiding means through the sphere of action of said point grinding means, said second guiding means and said end grinding means. 105
17. A pointing machine comprising a rotatable turret, a chuck carried thereby for holding the work to be pointed, a guide plate for positioning the work within said chuck, a grinding wheel positioned in proximity to said turret for pointing the work within said chuck, a second guide plate for re-positioning the work within said chuck, said plate having an arcuate tapered slot for receiving the point of the work, a second grinding wheel for finishing the end of the pointed work, and mechanism for rotating said turret to carry the work successively from said first guide plate across the opera- 110
- 120
- 125
- 130

tive face of first grinding wheel, over said second guide plate, and across the operative face of said end finishing wheel.

18. A pointing machine comprising a rotatable turret, a rotatable chuck carried thereby for holding the work to be pointed, a guide plate for positioning the work within said chuck, a grinding wheel having a concave operative face positioned in proximity to said turret, a second guide plate, a second grinding wheel for transversely finishing the end of the pointed work, means for operating said grinding wheels, means for continuously rotating said chuck, mechanism for continuously rotating said turret to carry the work from the first mentioned guide plate across the operative face of said first grinding wheel, over said second guide plate, and across the operative face of said second 10 grinding wheel, and means actuated by the rotation of said turret to open said chuck to release the work held therein when said work is carried over said guide plates, and to close 20

said chuck upon said work when carried into operative relation with said grinding wheels. 25

19. A pointing machine comprising a rotatable turret, a plurality of independently rotatable chucks carried thereby for holding the work to be pointed, a grinding wheel positioned in proximity to said turret for initially grinding a point upon said work, a second grinding wheel positioned in proximity to said turret for completing the point upon said work, a third grinding wheel for transversely finishing the end of the pointed work, means for rotating said chucks, and mechanism for rotating said turret to carry the work into operative relation successively with said grinding wheels. 30 35

In testimony whereof I have signed my name to this specification in the presence of two subscribing witnesses.
